UNITED STATES PATENT OFFICE.

WILLIAM H. WOOD, OF CLEVELAND, OHIO.

DESIGN FOR A REFLECTOR ATTACHMENT FOR AUTOMOBILE-HEADLIGHTS.

49,293.

Specification for Design.

Patented June 27, 1916.

Application filed April 15, 1916. Serial No. 91,496. Term of patent 14 years.

To all whom it may concern:

Be it known that I, WILLIAM H. Wood, a citizen of the United States, and a resident of Cleveland, in the county of Cuyahoga and State of Ohio, have invented a new, original, and ornamental Design for Reflector Attachments for Automobile-Headlights, of which the following is a specification, reference being had to the accompanying drawing, forming part hereof, wherein—

Figure 1 represents a front elevation of

a lamp reflector embodying my invention, Fig. 2 a vertical longitudinal central sectional view of the same.

I claim:

The ornamental design for a reflector attachment for automobile headlights as shown.

WILLIAM H. WOOD.

Witnesses:

I. L. STOHLMAN,

HUGH B. MCGILL.
